H. Carlson
ATTORNEY

UNITED STATES PATENT OFFICE.

FREDERICK JOSEPH LIOMIN, OF GLEN RIDGE, NEW JERSEY.

MOLD LOCK.

Application filed April 18, 1922. Serial No. 555,452.

To all whom it may concern:

Be it known that I, FREDERICK JOSEPH LIOMIN, a resident of Glen Ridge, in the county of Essex and State of New Jersey, have invented certain new and useful Improvements in Mold Locks, of which the following is a specification.

This invention relates to concrete molds and it more especially appertains to means for locking together the component parts of such contrivances.

The main object of the invention is to provide an improved lock of the character described, which shall be both a time and labor saving appliance as compared with devices heretofore used for the purpose of interrelatively locking panels of concrete molds to the supports or studding thereof.

Another object is to produce a lock of the nature set forth capable of holding together firmly without slipping, a plurality of mold sections composed of panels and studding, so that they can be shifted as a unitary whole, whenever the completion of each division of the work permits.

A further object is the production of a lock of the type specified so constructed and arranged that a comparatively small number of duplicates thereof is required to be handled in order to obtain the necessary clamping action upon the detachable parts of the mold.

Still another object is the provision in a lock of the class mentioned, of elements devoid of screw-threads and other parts liable to become clogged up with concrete, and which shall free itself from the latter when applied in operative position.

A still further object is to furnish a lock of the kind referred to, admitting of duplicates thereof being employed, without interference, on opposite sides of the supports or studding, and which will neither weaken the latter, nor require the same to be made excessively deep to withstand imposed strains.

An additional object is to supply a practical lock of the genus alluded to comprising few and simple elements, light but strong and durable, readily erected or taken down, conveniently operated as well as easily maintained in working order, besides amenable to low cost of manufacture.

Other objects and advantages of the invention will become apparent as the specification proceeds.

With the aforesaid objects in view, the invention consists of the novel combinations and arrangements of parts hereinafter described in their preferred embodiments, pointed out in the subjoined claims, and illustrated on the annexed drawing, wherein like parts are designated by the same reference characters throughout the several views.

Generally described, the invention under consideration includes in its organization a substantially L-shaped member provided with an inclined slot in one leg thereof. This slot is capable of taking over an element projecting from a side flange of the removable mold panel, inwardly thereover. The other leg of the member is adapted to engage an outer abutment formed on the mold support or studding, while an inner abutment on the latter serves to receive the edge of the panel. A plurality of members and elements are arranged along the edges of each panel and when a force is applied endwise upon the members, the inclined slots in them exert a wedging action against the sides of the elements which is transmitted to the panels and press the same tightly toward the inner abutments, the members being applicable or removable independently of one another, on both sides of the studding.

The advantages of the invention as here outlined are best realized when all of its features and instrumentalities are combined in the one and same structure, but, useful devices may be produced embodying less than the whole.

It will be obvious to those skilled in the art to which the invention appertains, upon becoming conversant with the details thereof, that the same may be incorporated in several different constructions. The accompanying drawing therefore, is submitted merely as showing the preferred exemplification of the invention.

In the said drawing:—

Figure 1 is a fragmentary side view of a panel and one of its supporting studs, associated in a concrete mold, showing the application thereto of this improved lock;

Fig. 2 is a partial edge view of the lock shown in the preceding figure, looking from the right hand side thereof; and

Fig. 3 is a section taken transversely of Fig. 2, on the line 3—3, looking upwardly in the direction pointed out by the arrows thereto appertaining.

Referring now to these views for a detailed description of the invention exemplified, the known parts of a concrete mold wherewith this new lock coacts, have been 5 designated by reference letters, instead of numerals, as used to denote the present improvements, since the said parts are not claimed as pertaining to the latter, except in so far as they may form therewith legitimate combinations of elements capable of 10 yielding novel and useful results.

"A" represents one of the supports or studding posts, shown as built up of structural steel beams B, which may be of Z-section 15 and have their web portions (B) set apart so as to provide a sufficient space therebetween. The larger flanges C of these Z-beams which are turned from each other, face also the interior of the mold where the concrete is poured. A plate D is secured on the exterior side of the support to the beams' outer flanges E, that point one toward the other. Suitably fastened within the space intermediate the said beams, is 20 a strip of wood F located flush with the flanges C at the base thereof and used for instance to attach the means which carry the rods employed to reinforce the concrete, in a manner well known. At G is indicated 25 a portion of a detachable mold panel having an offset flange H overlying one of the flanges C of the support A.

The parts hereinabove referred to constitute a characteristic embodiment of steel molds as found in modern practice for casting concrete structures of various kinds. However, the improvement to the existing 30 constructions, now to be outlined in detail, can equally as well be incorporated with composite molds made of wood and metal, or even of wood alone, with minor modifications.

From the inner edge of the panel flange H, extends upward or outwardly at substantially right-angles thereto, a lip or rib 11. Placed adjacent to and closely following the latter, preferably on the side thereof nearest the panel plate G, is a strengthening bar 13, of about the same height as the said 35 lip 11. It will be noticed with particular reference to Fig. 3 of the annexed drawing, that both the lip or rib 11 and the said bar 13, are so situated as to lie free and clear of the overhanging edge of the connecting or tie plate D on the outer side of the supporting post A. By positioning these parts in the manner described, the mold panel in its entirety can readily be withdrawn without disturbing any of the supports or the other panels ordinarily associated therewith. Altho the up or outstanding rib 11 has been illustrated as constituting a continuation of the flange H, while the bar 40 13 is a separate adjunct, it is obvious that 45 these parts could be either integral with,

or both affixed as a unitary piece to the panel, depending upon the conditions encountered in practice.

At 15 is represented one of the stud-like elements which project from the bar 13, preferably overhanging the panel flange H. These elements are located at predetermined distances apart along the edges bordering each panel, and may be either of cylindrical or oblong cross-section. As 50 shown in Fig. 1, the reference character 15^a is used to point out the permissible variation in form of the said elements, which this view exemplifies. Stud elements possessing both of the contours mentioned can also be 55 employed in conjunction with the panels, being in such a case preferably so arranged that the larger sizes of the elements will be used where the strain or pressure imposed on a panel is the most severe. These 60 elements and the bar 13 which carries them may be secured to one another and to the rib 11 and flange H by any appropriate means, for instance by electric welding, so as to unite them into a solid entity.

Coacting with the said element 15 (or 15^a) and the under face of the tie-plate D, is a wedge or key member 17. The latter consists preferably of an angular or L-shaped body having one leg 19 thereof bearing against the outer or upper surface of the stud element, while its other leg 21 takes under the overhanging portion of the said plate D. The leg 19 of the said key member extends inward or downwardly at approximately right-angles to the panel G and closely follows the stiffening bar 13 so as to be guided thereby. This leg has a bearing face 23 on the underside thereof, which is inclined or slopes inwardly away 105 from the said other leg 21, the latter running parallel with the plate D or flanges C. When a driving force or pressure is applied to the larger end 25 of the member 17, a wedging action is produced both in an outward direction along the contacting surfaces of the leg 21 with the plate D, and inwardly by the bearing face 23 exerting a thrust upon the thereto appertaining stud element.

In order to steady the member 17 and prevent its leg 19 to cant or tilt away from the stud element carried by the bar 13, another bearing surface 27 is provided on an extension 29 of the said leg, which extension may be directly connected to the latter by a part 31 formed integral therewith, as seen to best advantage in Fig. 1. It will be perceived on inspecting the figure last named, that the bearing surfaces 23 and 27, constitute the opposed parallel sides of an open ended obliquely disposed slot or gap 33, which terminates at 35, a certain distance from the free or bottom edge 37 of the leg 19. The before mentioned lower or inner bearing surface 27 130

not only maintains the key member 17 in proper guiding relation with the stud element, but it serves also to pull or drag away the leg 21 from the projecting ledge of the tie-plate D, when the larger end 39 of the extension 29 is tapped or rapped with a hammer, or the like. Owing to the open nature of the slot 33 and the comparatively short working faces of the therewith coacting stud element (15 or 15^a), any concrete or cement which may happen to become lodged upon or adhere to either of them, will easily be knocked off when these parts are driven together or apart. In other words, the member and co-operating element are self-cleaning in that respect.

From the foregoing it will be apparent, that there is no weakening of the supporting posts by the key members, and the former do not need to be made excessively deep to accommodate the latter or to resist the strains produced thereby, nor will the said members interfere with the application or operation of one another if placed in opposed relation on the sides of the said studing A. In view of the fact that the contacts of the panel flange H and the leg 21 with the surfaces C and D respectively engaged thereby, are rather extended, while the binding produced intermediately thereof, upon the stud element is quite intense on account of the small working areas of the parts in engagement, it will be understood that the hold or grip becomes so firm that sections of the mold including several panels and supports, can be transported or hoisted in one piece, as the work for which they are used in progressing, for instance, in making concrete walls, piers or arches.

The key members themselves are of compact and strong construction and not liable to get out of order even with the rough usage commonly received. Besides, as the members are of fair size, the chance of their being lost in the dirt around places where erection is going on, is much less than with pins, bolts and nuts now in prevalent use. The method followed in applying the keys to, or stripping them from the molds is so simple that the lowest class of labor employed can quickly learn to dexterously handle the same. The key engaged elements 15 (15^a) are sufficiently projecting to afford gripping means wherewith the panels may be manipulated when placed into or out of their assigned positions. These elements preferably have their exterior surfaces hardened to enable them better to resist wear and tear incidental to driving the wedge keys thereover or backing them off the latter.

While a certain preferred embodiment of this device has been shown and described, it will be understood that changes in the form, arrangements, proportions, sizes and details

thereof may be made, without departing from the scope of the invention as defined by the appended claims.

Having described my invention what I desire to secure by Letters Patent and claim, is:-

1. In a mold of the character described, the combination of an exteriorly and interiorly flanged support, a panel detachably bearing on the interior flange thereof provided with a rib, and a member adapted for wedgewise insertion intermediate the inner side of said rib and the exterior flange of said support, acting to force said panel against the latter.

2. In a mold of the character described, the combination of spaced apart supports having extended inner and outer overhanging projections in approximate parallelism with the mold space, a detachable panel carried by the inner ones of said projections including a rib extending substantially from the edge thereof, and a wedge member one side of which is adapted to engage the inner face of said rib while its other side finds an abutment against the outer projections of said supports.

3. In a mold of the character described, the combination of a support, a disconnectible panel coacting with the mold side thereof, an element substantially parallel to said panel carried thereby in proximity to the same, and a member capable of engaging said element together with the far side of said support so as to exert a wedging action therebetween and force the panel against the support on the near side.

4. In a mold of the character described, the combination of spaced supports, a panel separately held thereby, embodying a rib near its inner edge, an element extending from said rib having its axis in parallelism with said panel, and a member adapted to take over said element capable of exerting a thrust against the same and the outer part of one of said supports, so as to force the panel upon the latter.

5. In a mold of the character described, the combination of a panel included in the side thereof, a support against which one edge of said panel rests, a rib projecting from the latter adjacent said edge, an element extending over the panel inwardly from said rib, a member offset relatively to said element and said support capable of exerting a binding action upon both of the last named parts, and means coacting with said member to maintain it in operative relation with said parts.

6. In a mold of the character described, the combination of a support comprising inner and outer abutments, a panel having one edge thereof coacting with the inner one of said abutments, said edge being provided with a reinforced rib, an element offset

- therefrom, a lock member including angularly disposed legs in engagement with said edge of the panel against the abutment first element and the outer one of the abutments, respectively, and means with one of said legs cooperating with the element to maintain said member in operative alignment therewith and the last mentioned abutment.
7. In a mold of the character described, the combination of spaced supports, a removable panel therebetween provided with a reinforced rib near one edge, stud elements projecting at given distances apart from said rib, and a lock member including an inclined seat adapted to detachably engage one or the other of said elements, being capable of exerting a wedge action upon the same and the adjacent one of said supports, thereby forcing said panel against the latter.
8. In a mold of the character described, the combination of supports spaced apart, a panel detachably engaging one of the latter provided with a rib near its inner edge, a stud element of elongate cross-section extending from said rib, said element having the major axis of its section obliquely disposed relatively to said panel, and a lock member coacting with one of said supports, said member being obliquely slotted to take over the element and adapted when forced thereover to press the therewith connected panel against the same one of said supports.
9. In a mold of the character described, the combination of a support having inner and outer abutment flanges, a panel arranged to rest at one edge thereof upon the inner one of said flanges, said edge being provided with a rib, a strengthening bar following the latter, a stud element carried by said bar, and an L-shaped member formed with an oblique slot in one of its legs adapted to engage said element while its other leg coacts with the outer flange, the construction and arrangement being such that the forcing of
10. In a mold of the character described, the combination of spaced supports, a panel therebetween, an element carried by said panel, and a clamping member engaging one of said supports having a gap coacting with said element, the construction and arrangement being such that driving of said member in one direction wedges it against the thereto appertaining support with a face of said gap bearing on one side of the element, while a counter acting force causes the other face of the gap to exert a thrust upon the opposite side of the element, thereby releasing the clamping pressure intermediate the panel and the said support.
11. In a mold of the character described, the combination of a support having substantially parallel flanges, a panel detachably bearing upon one of the latter, a rib projecting approximately at right angles from said panel, an element extending over the panel from said rib, and a longitudinally insertable and removable locking member having a diagonally disposed open-ended gap adapted to engage said element intermediate the same and the other one of said flanges.
12. In a mold of the character described, the combination of spaced apart supports including inner and outer abutments, a detachable panel adapted to bear on the inner one of said abutments and comprising a rib rising substantially from the edge thereof, an element projecting sidewise from said rib, and a member having an open-ended inclined gap forming a double wedge therein enabling it to engage said element alternately on either side between the face of the rib and one of the abutments.

FREDERICK JOSEPH LIÓMIN.
